[57] ABSTRACT

A compact, portable massaging device for providing, by vibrating, gentle massage for remedial or hygienic purpose, which is fabricated in the form of a cushion and which comprises a motor, a pair of eccentrically rotatable vibrator elements for producing vibrations through a housing structure, and a plurality of coil springs for amplifying the vibration. These motor, vibrator elements and housing structure are covered with sponge material to enable the device to be used as a cushion.

FIG. 1

FIG. 2

MASSAGING DEVICE

The present invention relates to a massaging device and, more particularly, to a portable massaging device fabricated in the form of a cushion and designed to provide, by vibrating, gentle massage for remedial or hygienic purposes.

Specifically, the massaging device of the present invention is intended for use by an automobile driver in his automotive vehicle without disturbing the freedom of vehicle steering behaviour of the driver while giving gentle massage to the driver sitting or reclining on the cushion type massaging device placed on the vehicle seat.

According to a conventional massaging device of a similar character, a vibrating unit is accommodated in place within a sealed, rigid container which is in turn covered with sponge material made, for example, of polyurethane foam. The container is of a substantially orbicular shape and has a pair of opposed circular flat areas, between which the vibrating unit is housed within the container in the following manner. The vibrating unit comprises an electrically operated motor having a drive shaft of which the both end portions are outwardly extended from the body of the motor and a pair of shaped plate members rigidly mounted on the both end portions of said drive shaft for eccentric rotation below and above the circular flat areas within said container.

In the conventional massaging device of the above construction, as the motor is operated causing the plate members to eccentrically rotate about the motor drive shaft, the container undergoes a swelling motion by the effect of a centrifugal force acting on the eccentrically rotated plates. The swelling motion, that is, vibration, is then transmitted through the sponge material to the user sitting or reclining on the massaging device. However, this conventional massaging device has various disadvantages. In other words, since it has been primarily intended for use in home, the size is relatively bulky and, if it is possible to make the device compact, the massaging coverage is disadvantageously limited. In addition, since the eccentrically rotatable plates are each rotated in the plane parallel to the flat areas of the container and, hence, the body surface of the user where massage is desired, no substantially comfortable vibration or massage is available.

Accordingly, an essential object of the present invention is to provide a compact, portable massaging device which provides gentle massage to the user uniformly over the entire body surface where massage is desired, with substantial elimination of the disadvantages inherent in the conventional massaging device.

Another important object of the present invention is to provide the massaging device of the above described type which is fabricated in the form of a cushion and which can be used as a cushion when the device is not desired to be operated as a massager.

A further object of the present invention is to provide the massaging device of the above described type which can be operated with an electrical power of low voltage available, for example, from a power outlet for hand lamp or cigarette-lighter usually provided in the automotive vehicle.

A still further object of the present invention is to provide the massaging device of the above described type which can be manufactured at lower cost than re-

quired in the conventional massaging device with an improvement of performance and durability.

According to a preferred embodiment of the present invention, the massaging device comprises a micromotor of a type having a drive shaft outwardly extending from the both sides of the body of the motor in the longitudinal direction, a pair of vibrator elements rigidly mounted on respective free ends of said drive shaft for eccentric rotation, a pair of joined plate members having outwardly recessed portions, respectively, at their substantially intermediate portions, forming a cavity in which said micromotor and said vibrator elements are accommodated, a plurality of coil springs each extending from the joined plate members for transmitting to a remote location vibrations produced upon eccentric movement of said vibrator elements, and a soft or elastic covering encircling the joined plate members and the coil springs.

In the above construction of the massaging device according to the present invention, one of the most essential features resides in that the eccentric movement of each one of the vibrator elements is effected in the plane substantially perpendicular to the plane of the joined plane members and the plane of the longitudinal axis of the coil springs so that vibrations can be uniformly transmitted to the user thereby to provide gentle massage over the body surface where it is desired.

The provision of the coil springs is effective to transmit the vibrations away from the source thereof towards the periphery of the covering thereby to permit the whole area of the massaging device to produce a massaging action.

Furthermore, because of being compact in size and light in weight, the massaging device of the present invention, if placed between the back of the automotive vehicle driver and the vehicle seat-back, will not disturb the freedom of steering operation of the driver as hereinbefore described, but he can enjoy being massaged comfortably while driving his vehicle for the remedial purpose.

These and other objects and features of the present invention will become apparent from the following description taken in conjunction with the preferred embodiment thereof with reference to the accompanying drawings, in which;

FIG. 1 is a schematic diagram showing a sectional top plan view of a massaging device constructed in accordance with the present invention, and

FIG. 2 is a schematic diagram showing a cross-sectional view taken along the line II-II in FIG. 1.

It is to be noted that, for the sake of facilitating an easy understanding of the present invention, it will be described as fabricated in the square shape.

Referring now to the accompanying drawings, the massaging device is fabricated in the form of a cushion of substantially square shape, which generally comprises a vibrator unit 10, a vibration amplifying unit 20 and a covering 30.

The vibrator unit 10 includes a micromotor 11 of which the body is preferably of cylindrical shape and having a drive shaft 12 outwardly extending from the both sides of the body of said micromotor 11 in alignment with the longitudinal axis of said micromotor, and a pair of solid members 13 rigidly mounted on the drive shaft 12 on both sides of the body of said micromotor 11 for eccentric movement with respect to the longitudinal axis of said drive shaft 12. Rigid mounting of

each one of the solid members 13 on the drive shaft 12 may be carried out by fastening a screw 14 tapped on to the drive shaft 12 through the solid member 13. Preferably, each one of the solid members 13 is of a substantially triangular shape as shown in FIG. 2 and the both of which are mounted on the drive shaft 12 in an eccentrically offset manner as clearly shown in FIG. 1.

The vibrator unit 10 further includes a pair of plate members 15 each formed at its substantially intermediate portion with an outwardly recessed portion 15a so that, when said both plate members 15 are joined together by a suitable joining method, such as by the use of a plurality of bolts and nuts or by spot welding, said outwardly recessed portions of said plate members forms a cavity 16 for accommodating therein the motor 11 and holding the motor 11 in place within the cavity 16 through a plurality of elastic ring members 17 mounted on the body of the motor 11. Instead of using the elastic ring members 17, the motor 11 may be mounted in the outwardly recessed portion 15a of either of the plate members 15 and fitted in place by the use of a plurality of set screws tapped into the body of the motor 11 through the plate member 15.

The vibration amplifying unit 20 includes a plurality of coil springs 21, only four of which are employed in the illustrated embodiment, each having one end rigidly connected with a corresponding one of corner portions of the plate members and the other end extending away from the vibrator unit 10. Connection between the end of each one of the coil spring 21 and the vibrator unit 10 is preferably made in such a manner that said end is sandwiched between the both plate members 15 and then spot-welded as clearly illustrated in FIG. 2.

The vibrator unit 10 and the vibration amplifying unit 20 are both sandwiched by the covering 30 consisting of a pair of individual layers of synthetic sponge material, such as made of polyurethane foam, bonded to each other with the vibrator unit 10 and the amplifying unit 20 stationarily held therebetween.

Reference numeral 9 shown in FIG. 1 indicate a lead wire for connecting the motor 11 to a power outlet (not shown) through a suitable switch (also not shown) so that the electrical power necessary to operate the motor 11 can be supplied when the switch is turned on.

In assembling the massaging device according to the present invention, what is necessary to mount the motor 11 in the cavity 16 is to place the motor, the body of which is mounted with the elastic ring members 17 in spaced relation and the drive shaft is mounted with the solid members 13, in the recessed portion 15a of either of the plate members 15, the other plate member 15 being subsequently placed on the motor mounted plate member 15, and then to join the both plate members 15 by spot-welding as at 8, thus permitting the motor 11 to be firmly held in the cavity 16 defined by the recessed portions 15a.

The coil springs 21 are thereafter spot-welded as at 7. A combination of the units 10 and 20 is placed on either of the first and second layers 31a and 31b and the other layer 31b or 31a is subsequently placed on the layer 31a or 31b by the use of a bonding agent applied on the entire surface of the layer to be joined to the other.

Although not shown, the covering 30 carrying the units 10 and 20 is, at the time the massaging device is to be placed on the commercial market, encircled with a suitable bag for preventing the covering 30 from being contaminated during a long period of use.

In the construction as hereinabove described the other free end of each one of the coil springs 21 is preferably provided with a suitable weight 22 in the form of a set screw for enabling the vibrations to be regularly and uniformly transmitted through the coil spring.

Furthermore, the greater the number of the coil springs 21, the more the vibrations can be obtained over the substantially entire surface of the massaging device. In addition, through the coil springs have been described as radially outwardly extending from the vibrator unit 10, they may be arranged in the form of a spider web.

From the foregoing description, it has now become clear that the vibrations produced upon eccentric motion of the both solid members 13 can be transmitted from the plate members 15 to the peripheral edge portions of the cushion, i.e., the massaging device, to provide gentle massage to the user sitting or reclining on the cushion.

The massaging device of the present invention can be intended for use in home. In this case, the use of an AC-DC converter, which may be provided with a voltage regulator if the motor 11 is designed to operate with lower voltage than the power source voltage, is recommended, which is to be inserted between the motor and the power source.

Although the present invention has been fully described by way of example with reference to the attached drawings, it is to be noted that various changes and modifications are apparent to those skilled in the art. For example, most spot-welds described as effected in the preferred embodiment may be replaced by the use of screws or other suitable fastening members. Therefore, unless otherwise such changes and modifications depart from the scope of the present invention, they should be construed as included therein.

What is claimed is:

1. A cushion type massaging device usable for remedial or hygienic purposes which comprises drive means having a drive shaft, at least one vibrator element eccentrically rotatably mounted on said drive shaft, a housing structure for said drive means and said vibrator element which generates vibrations upon eccentric movement of said vibrator element about said drive shaft, a plurality of coil springs each connected with said housing structure for amplifying said vibrations and transmitting said vibrations away from said housing structure, and a protective covering made of synthetic foam material and encircling said housing structure with said drive means therein and said plurality of coil springs whereby, when said drive means is operated, a massaging action can be provided to the user sitting on or reclining on the device through a substantially entire surface of said covering.

2. A cushion type massaging device as claimed in claim 1, wherein said drive means comprises a micro-motor.

3. A cushion type massaging device as claimed in claim 1, wherein said housing structure comprises a pair of plate members each formed at a substantially intermediate portion with an outwardly recessed por-

tion which forms, when said both plate members are joined together, a cavity and said drive means having said drive shaft carrying said vibrator element is housed within said cavity.

4. A cushion type massaging device as claimed in claim 1, wherein said plurality of coil springs each have one end thereof connected with said housing structure and the other end freely extending away from said housing structure.

5. A cushion type massaging device as claimed in claim 4, wherein the other end of each one of said coil springs is provided with a weight for enabling the vibrations, transmitted through the coil spring, to be regularly and uniformly produced along the lengthwise direction of said coil spring.

6. A cushion type massaging device as claimed in claim 1, wherein said covering comprises first and second layer of polyurethane foam, both bonded to each other with said housing structure and said amplifying means sandwiched therebetween.

7. A cushion type massaging device usable for remedial or hygienic purposes which comprises an electrically operated motor having a drive shaft extending from both sides of the body of said motor, a pair of vibrator elements eccentrically rotatably mounted on both free ends of said drive shaft, a housing structure for said motor having said shaft carrying said vibrator elements which generates vibrations upon eccentric movement of said vibrator elements about said drive shaft, a plurality of coil springs each connected with said housing structure for amplifying said vibrations and transmitting said vibrations away from said housing structure, and a protective covering made of synthetic foam material and encircling said housing structure with said motor therein and said plurality of coil springs whereby, when said motor is operated, a massaging action can be provided to the user sitting or reclining on the device through a substantially entire surface of said covering.

8. A cushion type massaging device as claimed in claim 7, wherein said motor is mounted with a plurality of elastic ring members in spaced relation and wherein said housing structure comprises a pair of plate members each formed at a substantially intermediate portion with an outwardly recessed portion which forms, when said both plate members are joined together, a cavity, said motor being suspended within said cavity through said elastic members and firmly held in place within said cavity.

9. A cushion type massaging device as claimed in claim 7, wherein said plurality of coil springs each have one end thereof connected with said housing structure and the other end freely extending away from said housing structure.

10. A cushion type massaging device as claimed in claim 9, wherein the other end of each one of said coil springs is provided with a weight for enabling the vibrations, transmitted through the coil spring, to be regularly and uniformly produced along the lengthwise direction of said coil spring.

11. A cushion type massaging device as claimed in claim 7, wherein said covering comprises first and second layer of polyurethane foam, both bonded to each other with said housing structure and said amplifying means sandwiched in place therebetween.

12. A cushion type massaging device usable for remedial or hygienic purposes which comprises an electrically operated motor having a drive shaft extending from both sides of the body of said motor, a pair of vibrator elements eccentrically rotatably mounted on both free ends of said drive shaft, a pair of plate members each formed at a substantially intermediate portion with an outwardly recessed portion which forms, when said both plate members are joined together, a cavity for accommodating therein said motor in a suspended manner, said joined plate members carrying said motor being capable of producing vibrations upon eccentric movement of said vibrator elements, means for amplifying said vibrations and transmitting said vibrations away from said housing structure, and a protective covering made of synthetic foam material and encircling said joined plate members with said motor in said cavity and said amplifying means whereby, when said motor is operated, a massaging action can be provided to the user sitting or reclining on said device through a substantially entire surface of said covering.

13. A cushion type massaging device as claimed in claim 12, wherein said amplifying means comprises a plurality of coil springs each having one end rigidly held between peripheral edges of said joined plate members and the other end freely extending away from said joined plate members.

14. A cushion type massaging device as claimed in claim 13, wherein the other end of each one of said coil springs is provided with a weight for enabling the vibrations, transmitted through the coil spring, to be regularly and uniformly produced along the lengthwise direction of said coil spring.

15. A cushion type massaging device as claimed in claim 12, wherein said covering comprises first and second layers of polyurethane foam, both bonded to each other with said joined plate members and said amplifying means sandwiched in place therebetween.

16. A cushion type massaging device usable for remedial or hygienic purposes which comprises an electrically operated motor having a drive shaft extending from both sides of the body of said motor, a pair of vibrator elements eccentrically rotatably mounted on both free ends of said drive shaft, a pair of plate members each formed at a substantially intermediate portion with an outwardly recessed portion which forms, when said both plate members are joined together, a cavity for accommodating therein said motor in a suspended manner, said joined plate members carrying said motor being capable of producing vibrations upon eccentric movement of said vibrator elements, a plurality of coil springs each of which is adapted to amplify and transmit said vibrations away from said joined plate members and has one end rigidly held between peripheral edges of said joined plate members and the other end freely extending away from said joined plate members, and a protective covering made of polyurethane foam material and consisting of first and second layers bonded to each other with said joined plate members and said coil springs sandwiched in place therebetween, whereby, when said motor is operated, a massaging action can be provided to the user sitting or reclining on said device through a substantially entire surface of said covering.

17. A cushion type massaging device as claimed in claim 16, wherein the other end of each one of said coil springs is provided with a weight for enabling the vibrations, transmitted through the coil spring, to be

regularly and uniformly produced along the lengthwise direction of said coil spring.

18. A cushion type massaging device as claimed in claim 16, wherein said plurality of said coil springs are radially outwardly extended from said joined plate members.

19. A cushion type massaging device as claimed in claim 1, wherein said coil springs extend radially outwardly from said housing structure.

20. A cushion type massaging device as claimed in claim 7, wherein said coil springs extend radially outwardly from said housing structure.

21. A cushion type massaging device as claimed in claim 7, wherein said vibrator element, which are eccentrically mounted on both free ends of the drive shaft are arranged in an offset relationship with respect to each other.

22. A cushion type massaging device as claimed in claim 13, wherein said coil springs extend radially outwardly from said housing structure.

23. A cushion type massaging device as claimed in claim 12, wherein said vibrator element, which are eccentrically mounted on both free ends of the drive shaft, are arranged in an offset relationship with respect to each other.

24. A cushion type massaging device as claimed in claim 16, wherein said vibrator element, which are eccentrically mounted on both free ends of the drive shaft, are arranged in an offset relationship with respect to each other.

25. A cushion type massaging device as claimed in claim 1, wherein said plurality of coil springs radiate from said housing structure in the form of a spider web.
